UNITED STATES PATENT OFFICE.

HALVOR O. HEM, OF KANSAS CITY, MISSOURI.

STEAM-ENGINE.

1,050,538.

Specification of Letters Patent. Patented Jan. 14, 1913.

Application filed February 12, 1912. Serial No. 677,154.

To all whom it may concern:

Be it known that I, HALVOR O. HEM, a citizen of the United States, residing at Kansas City, in the county of Jackson and

5 State of Missouri, have invented certain new and useful Improvements in Steam-Engines, of which the following is a specification.

This invention relates to steam engines of that type having separate intake and exhaust valves at each end of the cylinder, and 10 means whereby said valves are operated in a manner analogous to that of the Corliss type of valves, in which the intake valves are operated by releasing gear as distinguished 15 from the type of engine under consideration in which the intake valves remain positively connected with their actuating appliances, my special object being to produce a valve-actuating mechanism in which each intake 20 valve will be stationary on expansion and exhaust for about one-half of each revolution of the crank shaft and yet remain engaged with its actuating appliance in order that the engine may be operated at greater 25 speed than is possible with the Corliss engine.

A further object is to produce mechanism of the type outlined which will operate efficiently and embodies the desirable features 30 of simplicity, strength and durability.

With these objects in view the invention consists in certain novel and peculiar features of construction and combinations of parts as hereinafter described and claimed; 35 and in order that the invention may be fully understood reference is to be had to the accompanying drawings, in which:—

Figure 1, is a fragmentary plan view of a steam engine embodying my invention. 40 Fig. 2, is a face view of the same on a smaller scale, and also illustrates diagrammatically the connections between the crank shaft and the valve-operating mechanism. Fig. 3, is an enlarged vertical section of the 45 cylinder and the valves of the engine, and also shows in elevation, the mechanism for operating the valves. Fig. 4, is a detail perspective view of the mechanism for operating one of the intake valves of the engine. 50 Fig. 5, is an enlarged fragmentary section of the cylinder and an intake valve and shows diagrammatically the action of the

valve-operating mechanism. Fig. 6, is a similar view, showing one of the exhaust valves and the mechanism for operating the 55 same.

In the said drawings where like reference characters identify corresponding parts in all the figures, 1 is an engine, 2 the cylinder thereof, 3 the inlet ports, 4 and 4^a the intake 60 valves, 5 the exhaust ports, and 6 and 7 the exhaust valves.

8 and 10 are the arms of the intake valves and 9 and 11 are the arms of the exhaust 65 valves.

12 is the piston in the cylinder, and 13 the piston rod for connection in the customary manner to the cross head and crank shaft 14.

16 is a housing secured to the side of the engine frame near the cylinder, and 17 is a 70 bonnet projecting outward from said housing and in conjunction with the same forming a journal bearing for the rock shaft 18 provided at its front end with a crank arm 19, the connection between a variable throw 75. eccentric (not shown) and the crank arm 19 being indicated by the rod 20, Figs. 2 and 5.

Vertically below the shaft 18, is a stub shaft 21, and pivotally suspended therefrom is an exhaust rock-plate provided with a 80 forwardly-projecting pin 22 connected by a rod 23 (shown in Figs. 2 and 6) to another eccentric, not shown, on the crank shaft 14, and projecting outward and inward from the exhaust rock-plate at opposite sides of 85 pin 22, are pins 24 and 25, the former being adapted to be connected pivotally by a connecting rod 24^a to the exhaust-valve arm 9, and pin 25, to the exhaust-valve arm 11, by rod 25^a; said rods 24^a and 25^a being indicated by dotted lines.

26 is a rocker plate rigidly secured to and depending from shaft 18, and pivotally connected to the lower ends of the same are links 27, pivoted at their opposite ends to 95 the upper ends of links 28, pivotally connected at their lower ends to the outer ends of auxiliary crank arms 29, of suitably-journalized auxiliary rock-shafts 30, and the latter are provided with upwardly-projecting arms 31 connected by rods 32 (shown by single lines in full, in Fig. 5, and by single dotted lines, Fig. 2), to the intake valves 4 and 4^a. Pivotally pendent from fixed points

33 of the engine, are governor arms 34, pivoted at their lower ends to lever links 27 about medially thereof and forming a moving fulcrum for said lever links.

- 5 With the parts in the position shown most clearly in Fig. 3, it will be noticed that the intake valves are closed on lap. Assuming that the rotation of the crank shaft causes rod 20 to move in the direction indicated by 10 the arrow, Fig. 5, it will be seen that rocker-plate 26 swings in the same direction through points, *a*, *b*, *c*, *d*, *e*, and *f* and through lever link 27 imparts movement to link 28 in the direction indicated by the arrow adjacent 15 thereto in Fig. 5, through points *g*, *h*, *i*, *j*, *k*, and *l*, and that to accommodate this movement the governor arm 34 swings in the direction indicated by the adjacent arrow, Fig. 5, through a corresponding number of 20 points indicated on the dotted lines connecting the points *a* and *g*, *b* and *h*, *c* and *i*, *d* and *j*, *e* and *k*, and *f* and *l*, this movement occurring obviously without affecting the position of the valve. As the rod 20 re- 25 verses the movement of the crank arm 19, the latter swings back until it is again vertical, and in such movement returns parts 26, 27, 28 and 34 to their original position. As such reverse movement carries arm 19 beyond the position indicated, the governor 30 arm 34, through lever link 27, and link 28 rocks auxiliary shaft 30 so that its arm 29 shall move upwardly and its arm 31 toward the vertical plane of shaft 18, and therefore 35 through rod 32 swing valve arm 8 in the direction indicated by the adjacent arrow Fig. 5, and thus turn the connected valve 4 so as to open communication between port 3 and the interior of the cylinder, the parts being 40 so proportioned that until rocker-plate 26 attains the position "m" the valve remains on lap, as such movement of the valve at such time is approximately from point "n" to point "o". As the rocker-plate 26 moves 45 from point "m" to point "p", which is the limit of movement with maximum load in that direction, the valve moves rapidly from point "o" to point "q" and is sufficiently open to admit steam to the cylinder at maximum load and force the piston to the right, it being understood that as the left hand intake valve is operated as described, the right hand exhaust valve is opened to permit the steam ahead of the piston to dis- 50 charge from the cylinder. As the arm 19 swings on its said reverse movement beyond the vertical position and thus effects the opening of the left hand intake valve 4, it swings the right hand links 27 and 28 and 55 right hand governor 34 inoperatively without affecting the right hand intake valve. In other words it will be apparent that the movements of the crank arm 19 to the right of a vertical position and back to such posi-

tion result in the opening and closing of the 65 left hand intake valve and do not affect the position of the right hand intake valve, and that the movements of said crank arm to the left from a vertical position and back to such position effect the opening and closing 70 of the right hand intake valve without affecting the position of the left hand intake valve, and that during about one half of the revolution of the crank shaft, viz., while arm 19 is swinging from a vertical position 75 to the left and back again, the left hand valve is stationary and the right hand valve is opened and closed, and while swinging from a vertical position to the right and back again, the left hand intake valve is 80 opened and closed and the right hand intake valve remains stationary. It will also be apparent that the first half of the movement of the crank arm 19 to the right from its initial or vertical position, moves governor 85 link 34 in the same direction from its initial or full line position Fig. 5, to dotted position *r*, and in such movement lever link 27 causes the upper end of link 28 to start on its movement from its initial point, Fig. 5, 90 to point *s*, the action with maximum load swinging the bell crank until its arms 29 and 31 attain the positions shown by dotted lines *t* and *u* respectively.

Assuming that the piston is moving to the 95 left under expansion and that the exhaust valve 6 is performing its closing operation, it will be seen that the pressure within the cylinder between the piston and said exhaust valve and intake valve 4 is raised to 100 the amount required for compression and that under such pressure and the pressure of the steam from port 3 leading to valve 4, the valve is practically balanced. While thus balanced and as the piston stroke terminates, said valve starts to open through movement of crank arm 19 to the right from its vertical or initial position, the valve moving over its lap, that is from *n* to *o*. In the first part of said movement of the said crank 110 arm 19 and with the maximum load, the said crank arm swings its maximum distance so as to open the port widely from *n* to *q*, and on its return movement when crank arm 19 attains its central position, the valve is 115 closed. The travel of the crank arm 19 is variable, swinging to extremes, as shown in Fig. 5 with maximum load, and having a shorter range of movement between such extremes with a lighter load. With a light 120 load the arm 26 may travel only from *m* to *c*, on which travel the valve will only move back and forth on the lap—but as the load on the engine increases, the movement of the eccentric increases, and arm 26 may 125 travel to any point between the points *f* and *p*. It will therefore be understood that the valve will always travel the same on the

lap but that the port opening and the percentage of each revolution that the valve remains open, depends on the load.

The operations of the exhaust valve and 5 the connections thereto are old and are illustrated simply to show the relative positions of the various valves of the cylinder.

From the above description it will be apparent that I have produced an engine having 10 a cylinder provided with an intake valve at each end and mechanism whereby each of said valves remain inactive during one-half of each revolution of the crank shaft, and which in opening, moves slowly 15 for approximately one-third of its movement, and then rapidly for the remaining two-thirds of its movement, and which in closing will move rapidly until on lap and then slowly until it attains its limit of closing 20 movement, and it is to be understood that I reserve the right to make such changes as properly fall within the spirit and scope of the appended claims.

I claim:—

25 1. An engine comprising a cylinder, an intake valve, an arm therefor, a rocker plate, a lever link having a movable fulcrum between its ends and pivoted at one end to the rocker plate, and means linking the 30 other end of the lever link to the valve arm.

35 2. An engine comprising a cylinder, an intake valve, a rocker plate, a lever link having a movable fulcrum between its ends and pivoted at one end to the rocker plate, and means actuated by movement of the 40 other end of said lever link for operating the valve.

45 3. An engine comprising a cylinder, an intake valve therefor, a pair of auxiliary rock arms in rigid relation to each other, a rocker plate, connections between one of said rock arms and the valve, a link pivoted to the other of said pair of rock arms, a lever link pivotally connecting said rocker plate and said last-named link at the free 50 end of the latter, and a swinging governor pivoted at its free end to the lever link between the ends thereof and forming a movable fulcrum therefor.

55 4. An engine, comprising a cylinder, an intake valve therefor, an arm for said valve, a pair of rock arms in rigid relation to each other, a link pivotally connecting the free end of one of said pair of rock arms with the arm of the valve, a link pivoted to the free end of the other of said pair of rock arms, a rocker plate, a lever link pivotally connecting said rocker plate with the free end of the second link, and a suitable 60 swinging governor arm pivoted at its free end to the lever link between the ends of the same, the said second link and said governor arm projecting in opposite directions from the lever link.

5. An engine, comprising a cylinder, a 65 pair of intake valves therefor, a rocker plate, oppositely projecting arms, links pivoted to the outer ends of said arms, lever links connecting the first-named links with said 70 rocker plate, pivoted governors pivotally connected at their free ends to the said lever links, arms bearing a rigid relation to said rock arms, and suitable connections between 75 said rigid arms and the valves.

6. An engine, comprising a cylinder, a 80 pair of intake valves, a rocker plate, oppositely projecting rock arms, links pivoted to the outer ends of said arms, lever links connecting the first-named links with said 85 rocker plate, pivoted governors pivotally connected at their free ends to the said lever links, arms bearing a rigid relation to said rock arms, arms movable with the valves, and links pivotally connecting the free ends of said arms with the said rigid rock arms. 90

7. An engine, comprising a cylinder, an intake valve for each end thereof, a rocker plate adapted to swing successively from its initial position in both directions and back to such position, an arm rigid with 95 each valve, a pair of rock arms suitably pivoted at a fixed point on the engine, links connecting the free ends of said rock arms with the arms of the valves, a rock arm rigid with each of the first-named pair of rock 100 arms, a link pivoted to the free end of each of said rigid rock arms, a lever link pivotally connecting the free end of each of the last-named links with the rocker plate at opposite sides of and at equal distances from 105 its axis, and a pair of governors pivoted at their upper ends to fixed points on the engine and each pivotally connected at its lower end to one of the pair of lever links between the ends of the same. 110

8. An engine, comprising a cylinder, an intake valve for each end thereof, a rocker plate adapted to swing successively from its initial position in both directions and back to such position, an arm for each valve, a 115 pair of arms suitably pivoted at fixed points to the engine, links connecting the free ends of said arms with the arms of the valves, a rock arm rigid with each of the first-named pair of rock arms, a link pivoted to the free end of each of said rigid arms, a lever link pivotally connecting the free end of the last-named links with the rocker plate at opposite sides of and equal distances from its axis, a pair of governors pivoted at their 120 upper ends to fixed points of the engine and each pivotally connected at its lower end to one of the lever links, a crank arm rigid with the rocker plate, and means for swinging said crank arm. 125

9. An engine, comprising a cylinder, an intake valve therefor, and valve-operating means adapted under certain operations to

have no effect on the valve and under certain other operations to open and close the valve.

10. An engine comprising a cylinder, a valve therefor, a rock plate, and means whereby movement of the rock plate in one direction and back to its original position shall be inoperative as regards the valve and from said original or initial position in the

opposite direction and back to said initial position shall open and close the valve.

In testimony whereof I affix my signature, in the presence of two witnesses.
